CLAIM

An ornamental design for an adjustable height sink module, as shown and described.

DESCRIPTION

FIG. 1 is a top perspective view, of an adjustable height sink module, showing my new design;

FIG. 2 is a front elevational view thereof;

FIG. 3 is a top plan view thereof;

FIG. 4 is a side elevational view as seen from the left hand side of FIG. 1 with the other side view being a mirror image thereof;

FIG. 5 is a top perspective view, of an adjustable height sink module, with the sink portion in a lowered position;

FIG. 6 is a front elevational view thereof;

FIG. 7 is a top plan view thereof; and,

FIG. 8 is a side elevational view as seen from the left hand side of FIG. 5 with the other side view being a mirror image thereof.
